UNITED STATES PATENT OFFICE.

PHILIP H. CARLYON, JR., OF DUNKIRK, NEW YORK.

FITTING FOR HOT-WATER-RADIATOR CONNECTIONS.

1,141,611.

Specification of Letters Patent.

Patented June 1, 1915.

Application filed June 4, 1912. Serial No. 701,594.

To all whom it may concern:

Be it known that I, PHILIP H. CARLYON, Jr., a citizen of the United States, residing at No. 106 West Fourth street, in the city of Dunkirk, in the county of Chautauqua and State of New York, have invented a new and useful Fitting for Hot-Water-Radiator Connections, of which the following is a specification.

10 My invention relates particularly to hot water radiator systems, and has for its objects the swinging of either end of the fitting nearer to or farther from the floor, as the case may be, to permit of the connecting 15 of the inlet and outlet pipes thereto without trapping, retarding or shutting off, the inlet or outlet flow of the water to the radiator, and the further object of permitting the connecting of the inlet pipe to either end of said fitting and consequently 20 the outlet pipe to the other end; also the further object that the said fitting can be used with any ordinary valve and may also be used without any valves. Also the further 25 object of constructing the device on an arc of a circle is to permit the screwing of the fitting when in position on the radiator, to the right to raise hole 5 and lower hole 6, or by screwing, to the left to lower hole 5 and 30 raising hole 6, without causing a space or air pocket, in the high end of the fitting that would retard the circulation of the water when in use.

In the past all fittings which permit of connecting the inlet and outlet flow of water to and from hot water systems on the same end of the radiator, it has always been necessary to have the ends of the hot, and cold water pipes, which are to be connected to the radiator, project the same height from the floor, or surface, on which the radiator stands thereby requiring great care in installing the pipes, to have the ends project exactly the same height above the floor, and particularly so if it be a cement or tile floor, or causing great inconvenience in adjusting the said pipes after being cemented in, the tile floor.

I overcome the above objections by providing a fitting so constructed that the raising or lowering of either end will not interfere with the flow of water to or from the radiator, thereby eliminating the care heretofore necessary in placing the ends of 55 the hot and cold water pipes exactly the

same distance above the floor, or other surface, on which the radiators are placed.

I attain these objects by the mechanism, or fitting, shown and illustrated in the accompanying drawings, in which:

Figure 1 is an elevation in section of Fig. 3 taken on the curved line X—Y. Fig. 2 is an elevation of the same fitting, Fig. 3 is a plan view of the face or surface "A" on Fig. 2, and Fig. 4 is a section of a part of said fitting taken on line "A"—"B" in Fig. 2.

Similar letters and figures refer to similar parts throughout the several views.

In the drawings, 1 indicates the body of the fitting having cast thereon a threaded 70 nipple or projection 2 and bosses 3 and so cored out as to form the chambers C and D in said fitting with the partition 4 between them thus dividing the hot water fitting into two separate chambers. The fitting 1 is provided with tapped holes 5 and 6 in the 75 bosses 3 thus permitting the fitting to be attached to the inlet and outlet water pipes and at the same time keeping separate the incoming and outgoing water while in said 80 fitting. The partition 4 projecting beyond the nipple 2 separates or deflects the incoming and outgoing water in the radiator to which said fitting is attached.

In the use and application of said fitting 85 it will be seen that the threaded nipple 2 can be screwed in and attached to the radiator thus forming a pivot, or center, on which the remainder of the fitting revolves. It will be noticed by Fig. 3 that the fitting is 90 a segment of a circle and the center inlet water pipe hole 5 and outlet water pipe hole 6 are also located on a circular line. As heretofore stated, the inlet water pipe hole 5 may be used for the incoming or out 95 going water whichever the user desires. It will be further noticed that the inlet water pipe hole 5 being located to the one side of the nipple 2 with said nipple 2 as a pivot the fitting 1 may be turned, or 100 rotated, on said nipple 2 so as to raise the inlet pipe hole 5 which may be on either side, or lower the outgoing water hole 6, which may be on either side as desired without trapping, or cutting off the incoming or 105 outgoing water, and without interfering with the circulation of the water in any manner whatever. The hot water from the boiler can pass through the pipe opening 5 into the chamber C and through said chamber 110

C into the radiator and after passing through the radiator pass out of the chamber D and through the outlet pipe hole 6.

When the above described fitting is in position on the radiator and pipe hole 5 and pipe hole 6 are on a level horizontal line, with each other, the fitting may be screwed to the right thereby raising pipe hole 5 and lowering pipe hole 6, or screwing to the left thereby raising pipe hole 6 and lowering pipe hole 5 so as to make a difference of one inch in the height of said holes 5 and 6 without causing the top side of hole 5 when screwed to the right, and the top side of hole 6 when screwed to the left, to be any higher than the top side of nipple 2, thus doing away with the trouble and nuisance of having the incoming and outgoing water pipes exactly the same height above the floor, or surface, on which the radiator stands. This fitting can also be used with any ordinary valve, thus making it convenient to install. The fitting can also be used without valves should occasion require it. Numerous changes in minor de-

tail of the construction of the above described steam fitting may be made within the intended scope of my invention.

Having thus described my invention what I claim as new and desire to cover by Letters Patent is:

1. A radiator fitting having in one wall a passage divided by a partition, and in the opposite wall two passages spaced from each other, the latter passages being so located with reference to the first-named passage that when the partition is in a vertical plane the axes of the two passages will lie below a horizontal plane passing through the axis of the first named passage. 40

2. A hollow T-shaped radiator fitting having a substantially central passage in one wall and a plurality of passages in the opposite wall, the axes of all the passages lying on the arc of a circle.

PHILIP H. CARLYON, JR.
